(57) **CLAIM**

The ornamental design for a child resistant sanitizer bottle, as shown and described.

DESCRIPTION

FIG. 1 is a front perspective view of the child resistant sanitizer bottle of the instant invention;

FIG. 2 is a front plane view thereof;

FIG. 3 is a right side view thereof;

FIG. 4 is a rear plane view thereof;

FIG. 5 is a left side view thereof;

FIG. 6 is a top view thereof;

FIG. 7 is a bottom view thereof; and,

FIG. 8 is a perspective view with the cap removed from the bottle.

The hidden lines are for illustrative purposes only and form no part of the claimed invention.
